UNITED STATES PATENT OFFICE.

CHARLES A. REDMOND, OF LOS ANGELES, CALIFORNIA, ASSIGNOR TO DETROIT MOTOR GOVERNOR CORPORATION, OF DETROIT, MICHIGAN, A CORPORATION OF MICHIGAN.

SPEED-CONTROLLING DISTRIBUTER.

1,295,206.

Specification of Letters Patent.

Patented Feb. 25, 1919.

Application filed July 16, 1917. Serial No. 180,691.

To all whom it may concern:

Be it known that I, CHARLES A. REDMOND, a citizen of the United States of America, residing at Los Angeles, county of Los Angeles, and State of California, have invented certain new and useful Improvements in Speed-Controlling Distributors, of which the following is a specification, reference being had therein to the accompanying drawings.

10 In the operation of high speed internal combustion motors, it is frequently desirable to provide means for limiting the speed thereof, especially where they are used on trucks and other vehicles or tractors, the 15 road speed of which is preferably low.

This invention relates to a speed controlling distributor for the ignition system of an internal combustion motor for use in a place of this type which is arranged to prevent 20 racing or overspeed of the engine beyond a predetermined point.

The invention consists in the matters hereinafter set forth, and more particularly pointed out in the appended claims.

25 In the drawings,

Figure 1 is a plan view, partially broken away and in section, of a speed controlling distributor that embodies features of the invention;

30 Fig. 2 is a view in section taken on or about line II—II of Fig. 1;

Fig. 3 is a view in detail in side elevation of a centrifugal weight controlling mechanism; and

35 Fig. 4 is a view in side elevation taken from the opposite side of Fig. 3.

Referring to the drawings, a casing 1 of suitable design and material is arranged to be secured on the main frame or base 2 of an 40 engine, preferably being concentric with a timing shaft 3, and being held by a spring arm 4 that is suitably secured to the engine and that is arranged to bear with a slight extension 5 against a corresponding bearing 45 depression in the casing.

The shaft 3 runs in timed relation to the engine cycle by any suitable connection. It may be the cam shaft or particularly disposed timing shaft, or may be an extension 50 of the main shaft. A fitting 6 which in form is substantially a bell crank, or at least of suitable design for the purpose, is non-rotatably secured as by a pin 7 to the shaft 3 within the casing so that the end thereof 55 rotates close to contact plates 8 which are

set into an annular insulating body 9 of the casing. These segments correspond in number to the cylinders of the engine for which the device is arranged, and are each provided with a binding screw 10 or the like. 60

A contact lever 11 is pivoted as at 12, to one arm of the member 6 with a wiping block 13 thereof sweeping the face of the insulating band 9 and periodically contacting with the segments 8. It is held to its 65 work normally by a spring 14, the other end of which is secured to a centrifugally operated weight 15. The latter has a finger 16 and is pivoted as at 17 to the other arm of the bracket 6 opposite to the pivotal support 12 of the member 11, this finger overlapping and bearing against an extension 18 of the wiper lever 11. A boss or lug 19 on the inner face of the member 11, prevents or limits the inward movement of the lever 11 75 under the action of the finger 16.

In operation, and when at rest, the spring holds the wiper projected and the weight well retracted. When the engine is rotating the wiper point or block is yieldingly held 80 by the spring so as to sweep across the several contact plates until a predetermined speed for which the weight is adjusted, causes the latter to fly out and thereby retract the wiper, breaking the ignition circuit 85 and causing a reduction in speed of the engine until a predetermined maximum rate of speed is again reached.

As a result of this construction, a distributor is obtained which has all the advantages of the usual construction, it being understood that by means of an extension 20 the casing 1 may be turned angularly to advance or retard the spark in the usual manner, while at the same time operation of 95 the centrifugal weight prevents overspeed of the engine.

Obviously, changes in the details of construction may be made without departing from the spirit of my invention and I do 100 not care to limit myself to any particular form or arrangement of parts.

What I claim is:

1. A speed controlling distributor for the ignition system of an explosive engine, comprising the combination with an engine and a shaft therethrough, of a casing angularly adjustable on the engine casing, concentric with the shaft, a spring arm yieldingly maintaining the casing in adjusted position, 110

an insulating annulus in the casing, electric contacts embedded in the annulus concentrically with the shaft, a fitting on the shaft revolving within the annulus, a wiper member pivoted on the fitting to sweep the contacts, a weight member pivoted on the fitting and engaging the wiper member to retract the latter when the weight is projected, a spring interconnecting the wiper member and the weight to project the former and retract the latter, and a stop on the wiper member to limit the inward motion of the latter and the outward motion of the former.

2. The combination with an engine base and shaft therethrough turning in fixed relation to the cycle of the engine, of a casing angularly adjustable on the engine base concentrically with the shaft, a member frictionally engaging the casing and maintaining it in position, an insulating annulus in the casing concentric with the shaft, con-

tacts on the inner periphery of the annulus around the shaft, a fitting secured to the shaft to revolve within the annulus, a wiper member pivoted between the ends thereof on the fitting to sweep the contacts, a stop limiting the inward movement of the wiper, a centrifugal weight member pivoted between the ends thereof on the fitting with an unweighted arm contacting with the wiper member to force the latter inward when the weight moves outward, and a spring yielding connecting the free arm of the wiper and the weighted arm of the centrifugally operated member and acting to project the wiper and retract the weight.

In testimony whereof I affix my signature in presence of two witnesses.

CHARLES A. REDMOND.
